DOOR CLOSER VALVE

Robert S. Potter, Old Greenwich, Conn., assignor
to The Yale & Towne Manufacturing Com-
pany, Stamford, Conn.

Application August 17, 1931. Serial No. 557,629

4 Claims. (Cl. 16—51)

This invention relates to door checks of that type having means for controlling the movement of the door from a full-open position to a fully closed position. In door checks of this type, it is customary to permit the door to move rather swiftly during the initial closing movement, and then to change the door closing speed so as to obtain a desirable latching speed, in order to control more effectively the slight noise incidental to the last final latching movement of the door to its closed position.

This problem is a comparatively old one in the door closing art and was first approached by L. C. Norton in Patent 1,152,339 granted August 31, 1915 and owned by The Yale & Towne Manufacturing Company. Norton devised a single adjusting screw which was adapted to adjust a valve controlling the movement of the door through practically all of its closing movement to about 5°, this screw having a second portion for adjusting a second valve to control the final movement of the door during the last 5° of the door closing movement. The Norton device was faulty because the adjustment of the latching movement is accomplished by a flattened portion 22 which is so sensitive as to make door latching adjustment very difficult, so much so, that it can only be accomplished by an expert.

The problem of adjustment was once more attacked in the later Norton Patent 1,772,250 which recognizes this evil, and in which Norton was satisfied to permit for a constant non-adjustable closing speed and an easily manipulated latching speed adjustment.

It is the object of this invention to devise an adjustment mechanism which will be adapted to control, first, the adjustment of the regular closing movement up to about 5%, and then without disturbing this first adjustment substantially, to permit of a very fine and graduated adjustment of the latching speed. While the invention is a comparatively simple one, it solves a problem of long standing in the door closing art, and one which has been troublesome to the experts in that art.

Referring now to the drawing where a particular embodiment of my invention is shown, Fig. 1 is a partially cut open view of a typical door closing arrangement, showing the application of my invention thereto. Fig. 2 is a perspective view of a portion of the adjusting screw. Figs. 3, 4, and 5 are sections taken along the lines A—A of Fig. 1 and showing my adjusting screw in its several positions.

As will be readily understood, reference

numeral 1 represents the usual type of cylinder having movable therein a piston 2 equipped with a piston head 3, having the usual ball valve 4 mounted therein. The movement of the piston is caused by its contact with the gear sector 5 cooperating with the rack 6, the gear sector 5 being mounted on the shaft 7 which is rotated upon opening and closing movement of the door as will be readily understood by those skilled in the art.

A by-pass duct 8 connects the piston containing portion of the cylinder 1 with the body of the door closer, so as to permit the fluid to run from the cylinder 1 into the casing of the door closer to the rear of the piston when expelled in that direction by the movement of the piston as is readily understood by those skilled in the art. This movement of the piston against the fluid so as to expel the fluid through the by-pass duct 8, is controlled by the duct 8 and a pair of ports 9 and 10. The port 9, in addition to the port 10 will receive all the fluid during the major portion of the piston movement, and comprising 95% of the door closing movement. The movement of the piston head 3 into the door closing position will gradually cover entirely the port 9 so that port 10 will be the only port through which the liquid can flow during the last 5% of the door closing movement. It is therefore, readily seen that adjustment of the flow of liquid through the port 9 and the by-pass duct 8, will control the liquid flow and the door closing speed during the major part of the door closing movement. It will be readily seen that the control of the port 10 will be effective to regulate the final door closing or latching speed.

For the purpose of adjusting the various ports, I utilize an adjusting screw 11 having a screw threaded portion 12 which cooperates with a threaded bushing or insert 13 which is adapted to hold in position the usual oil washer 14 and the various other bearing means for the screw and valve. The adjusting screw 11 will then, through, its screw thread 12, rotate relatively to the bearing means, such rotation being adapted to control the position of portions of the screw for a purpose to be explained below.

The adjusting screw 11 is equipped with a tapering portion 14 which will be adapted for adjusting the opening of the by-pass duct 8, so as to determine the speed of the flow of fluid through the port 9 and the by-pass duct 8 during the major part of the door closing movement. The screw threaded engagement between the adjusting screw 11 and the bearing insert 13 is such that only a very slight movement of the adjust-

110

ing portion of the screw 14 will be obtained during each revolution of the screw 11. This will, of course, make adjustment of the main closing movement of the door comparatively simple, and will permit of rather fine work.

5 The adjusting screw 11 is further equipped with a portion 20 having a graduated groove 21 leading into the lateral passage 22 (Fig. 2). As will be readily understood, any liquid flowing through the port 10 will be controlled by this groove 21. 10 In the position of Fig. 3, it is obvious that the liquid will have to flow through the port 10, and the full length of the groove 21 and out through the passage 22, thus slowing up the latching movement considerably. In Fig. 4 the latching 15 movement will be considerably faster since the fluid will have a considerably shorter pathway to traverse. In Fig. 5, the latching speed will be very considerable since the fluid will have direct access to the duct 8 or port 9 through the 20 port 10 and the passageway 22.

The groove 21, as will be readily observed, is located on about 180° of the peripheral circumference of the adjusting screw 11, and is in the 25 same plane as the port. This permits of a very slow and graduated adjustment of the latching speed, while at the same time, the main closing speed controlled by the portion 14 of the screw, is maintained comparatively constant due to the 30 small amount of movement longitudinally of the screw 11 during 180° of rotation.

By this construction, I am thus able to obtain a very effective means of simultaneously adjusting the main closing movement and the latching speed, utilizing the single screw of the prior art 35 for the purpose. While I have shown one modification of my invention and a particular graduated groove, it should be understood that modifications of the same within the scope of the 40 appended claims will readily occur to those skilled in the art.

I claim:

1. In a door check, the combination with a 45 cylinder having a pair of valve ports leading to the cylinder chamber near one end thereof, of a single regulating screw having screw-threaded engagement with said cylinder and having a portion cooperating with one of said ports for adjusting the size thereof during a series of revolutions of said screw, and having a second portion 50 cooperating with the other of said ports for

adjusting the size thereof during each revolution of said screw, said portion comprising a graduated groove of varying depth in the plane of the port, and occupying the periphery of the screw for substantially 180° whereby to adjust said port opening from zero to a full opening during substantially 180°.

2. In a door check, a cylinder having a pair of valve ports leading to the cylinder near one end thereof, a single valve regulating screw having screw threaded engagement with said cylinder and having a portion cooperating with one of said ports for continuously adjusting the size thereof by a gradual rotation and movement of the screw relatively to the cylinder, and having a second portion cooperating with the other of said ports for adjusting the size thereof from minimum to maximum during substantially 180° rotation of said screw.

3. In a door check, a cylinder having a pair of valve ports leading to the cylinder near one end thereof, a single valve regulating screw having screw threaded engagement with said cylinder and having a portion cooperating with one of said ports for continuously adjusting the size thereof by a gradual rotation and movement of the screw relatively to the cylinder, and having a second portion cooperating with the other of said ports for adjusting the size thereof from minimum to maximum during a substantial rotation of said screw less than 360°, said portion embodying a circumferential graduated groove on the periphery of said screw.

4. In a door check, a cylinder having a pair of valve ports leading to the cylinder near one end thereof, a single valve regulating screw having screw threaded engagement with said cylinder and having a portion cooperating with one of said ports for continuously adjusting the size thereof by a gradual rotation and movement of the screw relatively to the cylinder, and having a second portion cooperating with the other of said ports for adjusting the size thereof from minimum to maximum during a substantial rotation of said screw, said portion embodying a circumferential groove of varying depth and occupying substantially 180° of the screw circumference, and communicating at its deepest point with a longitudinal escape groove on the screw surface.
